(57) **CLAIM**

I claim a new ornamental design for an oyster opener, as shown and described.

DESCRIPTION

FIG. 1 is a front, top, left side perspective view of an oyster opener showing my new design.

FIG. 2 is a front top right side perspective view of the oyster opener of FIG. 1;

FIG. 3 is a top plan view of the oyster opener of FIG. 1;

FIG. 4 is a front elevational view of the oyster opener of FIG. 1;

FIG. 5 is a rear elevational view of the oyster opener of FIG. 1;

FIG. 6 is a bottom plan view of the oyster opener of FIG. 1;

FIG. 7 is a left side elevational view of the oyster opener of FIG. 1;

FIG. 8 is a right side elevational view of the oyster opener of FIG. 1;

FIG. 9 is a rear bottom right side perspective view of the oyster opener of FIG. 1; and,

FIG. 10 is a rear bottom left side perspective view of the oyster opener of FIG. 1.

The broken lines in the disclosure are unclaimed subject matter.
